UNITED STATES PATENT OFFICE.

GOTTLÖB HONOLD, OF STUTTGART, GERMANY, ASSIGNOR TO THE FIRM OF ROBERT BOSCH, OF STUTTGART, GERMANY.

IGNITION FOR MULTIPLE-CYLINDER COMBUSTION-ENGINES HAVING IRREGULAR ORDER OF IGNITION.

1,124,022.

Specification of Letters-Patent.

Patented Jan. 5, 1915.

Application filed September 27, 1910. Serial No. 584,004.

To all whom it may concern:

Be it known that I, GOTTLÖB HONOLD, a subject of the Emperor of Germany, residing at Stuttgart, Germany, have invented 5 certain new and useful Improvements in Ignition for Multiple-Cylinder Combustion-Engines Having Irregular Order of Ignition; and I do hereby declare the following to be a full, clear, and exact description of 10 the invention, such as will enable others skilled in the art to which it appertains to make and use the same.

There have been recently employed in aero-technics, multiple cylinder combustion engines whose cylinders are arranged fan-fashion in one or more planes. The pitman rods of the individual pistons actuate either a single crank or several cranks having a definite angular arrangement. Such an arrangement of the cylinders establishes an irregular succession of individual ignitions. For this reason, the ignition for these engines by electric igniting machines is accompanied with great difficulties, because, 15 as is well known, the sparking voltage in these machines is always developed at the same angular position of the element that rotates in the magnetic field, so that the sparking voltage is available only at uniform periods, such as 90° or 180° in a two-pole machine. Consequently, it has heretofore been advisable to divide the cylinders of such combustion engines into separate 20 groups presenting a regular order of ignition, and to assign a separate ignition machine to each group; or to employ for the ignition a source of direct current as a dynamo or a battery. An increase of the number of the ignition machines for flying machines 25 motors is inadvisable on account of the attendant increase of weight. With batteries the disadvantage of unreliability of the ignition must be taken into account. Finally, in employing a direct current dynamo, difficulties in starting are encountered.

The present invention is based upon the consideration that in the construction of almost all such engines the angular differences between the crank positions corresponding to successive periods or instants of ignition have a common divisor. As soon as this condition is fulfilled, ignition can be produced with a single magneto at all points

required by the irregular order of ignition, if we allow the magneto to rotate uniformly 55 at such a speed that its succeeding periods of maximum voltage or sparking points occur at intervals equal to the common divisor. There may then be obtained a number of ignition sparks in excess of that required, but the excess may be prevented from interfering with the operation in various ways. For instance, the excess sparks may be consumed in those engine cylinders which contain no combustible gas at the 60 time. Or a special conductor can be provided in combination with corresponding provisions on the distributor to allow the excess ignition currents to traverse the conductor. Or the interrupter can be arranged 70 so that, at the times at which the ignition current is available but is not required, the armature winding may be closed or not opened so that no ignition current is produced.

For multiple cylinder engines arranged in fan-form, with an irregular order of ignition, the condition that the angular differences between successive ignitions shall have a common divisor may be fulfilled by making the angles of divergence of neighboring cylinders equal to the center angles of a regular polygon. For instance, for the operation of a fan-form three cylinder engine, whose cylinder axes form with each other 80 angles of 72° or $360^\circ/5$, the engine requires an order of ignition, which, in relation to the crank stroke, is expressed by the angles 85 144° , 288° and 288° , the greatest common divisor of which is 144 . Therefore, in accordance with the invention, instead of the irregular order of ignition a regular order 90 is provided in which the ignitions follow each other at periods equal to 144° of the crank strokes or 72° of the cam shaft stroke. 95 This is accomplished by interposing between the crank shaft and the armature shaft of the assumed (as an example) two-pole shuttle armature machine, gearing having the ratio of 144 to 180 or 4 to 5 ; or, in other 100 words, by treating the fan engine as if its cylinders were distributed about the crank shaft at equal angles of the value of the common divisor and wherein some of the cylinders are omitted. In the example 105 chosen we obtain in this way, for each two

revolutions of the crank shaft or one revolution of the cam shaft, five periods of maximum voltage or ignition points of the magneto, whereas only three are required for the operation of the engine. The two in excess are suppressed in accordance with the invention, in any of the ways hereinbefore referred to.

The drawings show several of a great number of possible exemplifications of the invention. All of the modifications shown relate to four-cycle engines.

Figure 1 is a diagrammatic illustration of a fan-form engine driving the crank shaft with three cylinders arranged adjacent to each other at angular displacements of 72° . Fig. 2 is the corresponding diagram of the order-of-ignition, in its relation to the cam shaft. Fig. 3 is a diagrammatic illustration of a star shaped five cylinder engine with like divergence of the cylinders, and Fig. 4 is the corresponding diagram of the order-of-ignition, in its relation to the cam shaft. Fig. 5 is a diagrammatic illustration 25 of an interrupter with five cams, which can be employed for the engine of Fig. 3, in accordance with the invention. Fig. 6 is a corresponding illustration of an interrupter with three wipers for the engine of Fig. 1. Fig. 7 is a representation of the corresponding distributer. Fig. 8 is a diagrammatic illustration of a six cylinder engine wherein the fan-form cylinders arranged in pairs act upon three cranks arranged 120° apart. Fig. 9 is an illustrative diagram of the relative piston positions of the engine of Fig. 8. Fig. 10 is the corresponding order-of-ignition diagram, in its relation to the cam shaft. Fig. 11 is the diagram of a star-form nine cylinder engine, and Fig. 12 is the corresponding order-of-ignition diagram, in its relation to the cam shaft. Fig. 13 is an illustration of the interrupter corresponding to the engine of Fig. 11; Fig. 14 is an illustration of the interrupter, and Fig. 15 an illustration of the distributer of the engine of Fig. 8. Fig. 16 is an illustrative diagram of a six cylinder engine in which there are three cylinders in one plane and three in another plane. Fig. 17 is the corresponding order-of-ignition diagram, in its relation to the cam shaft. Fig. 18 is the diagram of an eight cylinder engine wherein each four cylinders lie in a separate plane and actuate a common crank. The cranks of each group of four cylinders are set at 180° to each other. Fig. 19 is the corresponding order-of-ignition diagram, in its relation to the cam shaft. Fig. 20 illustrates the interrupter for the engine of Fig. 18, and Figs. 21 and 22 the interrupter and distributer for engine of Fig. 16. Figs. 23 to 25 show the construction of the distributer corresponding to the three kinds of engines illustrated with irregular

order of ignition. Fig. 26 shows, as an example, an operative system in accordance with this invention, wherein A represents the engine shown in Fig. 1, B an ordinary two-pole magneto generator driven from the engine by gearing C having a ratio of 2:5, whereby the ignition currents produced at intervals of 72° of the cam shaft by means of the interrupter D are conducted to the engine cylinders in proper order by means of the distributer E and connections F and G. The ignition currents in excess of those required by the engine are conducted by the segments s_2 and s_3 to the cylinders 2 and 3 near the ends of the respective strokes when no explosive gas is present therein, as will be noted later.

The radii shown in Figs. 2, 4, 10, 12, 17 and 19 indicate the angular position of the cam shaft at the sparking periods for the cylinders corresponding in numeration.

Fig. 2 shows the order of ignition of the fan-engine of Fig. 1. The cylinders follow each other in the series 1, 3, 2 in angular positions of the cam shaft of 72° , 144° and 144° . Between radii 3 and 2, and 2 and 1, are indicated in dotted lines the dividing lines of the inclosed angular positions, by which the irregular order-of-ignition diagram of the fan motor is converted into one of regular order, identical with Fig. 4 for the star-form five cylinder engine of Fig. 3. Thus, in order to ignite the fan-engine in accordance with the invention, there is included between the cam shaft and the armature shaft of the ignition machine, gearing having a ratio of 2:5.

In accordance with Fig. 5 there are provided for the interrupter, which is conceived as rotating at the same speed as the cam shaft, five cams equally spaced around its periphery. Care is taken that the current impulses produced by the cams 4 and 5 do no damage, by employing the distributor shown in Fig. 23. There are embedded in the insulating material of the distributer disk v of Fig. 23, three contact segments s_1 , s_2 and s_3 , which are successively engaged by the contact arm rotating with the cam shaft. The points 4 and 5 are connected with the points 2 and 3 respectively, by the segments s_2 and s_3 , and the ignition currents are conducted into the corresponding cylinders. Such occurs, however, at times at which these cylinders are at the end of their working stroke, and hence, when they contain no ignitable gas mixture and cannot therefore affect the operation of the engine.

If it is desired to prevent altogether the production of excess sparks, an interrupter cam-disk as shown in Fig. 6 may be used, wherein the cams corresponding to the missing cylinders 4 and 5 of the engine of Fig. 1 are likewise missing, so that, in spite of

the availability of the ignition current between the ignitions 3 and 2 and between 2 and 1, no current flows in the ignition circuit at these times. For this case a distributor disk in accordance with Fig. 7 suffices. It is now apparent that this arrangement may be applied for all fan-form engines, whose cylinder spacings are equal to the center angles of a regular polygon. The universal rule for the necessary gearing is that the ratio of the velocities of the armature shaft and the crank shaft must equal the ratio of angular separation of two successive periods of maximum voltage in the ignition machine to the greatest common divisor of all angular separations of crank positions that exist for successive ignitions.

The six cylinder engine illustrated in Figs. 8 and 9 requires the irregular order-of-ignition diagram of Fig. 10, and this is converted, by the insertion of the dotted dividing lines, in accordance with the invention, into the regular order of ignition of Fig. 12, which corresponds to the star-form nine cylinder engine of Fig. 11. The cylinder scheme of Fig. 11 is obtained from the cylinder scheme of Figs. 8 and 9 by rotating the pairs of cylinders 4, 5 and 7, 8, through the proper angles and imagining the cylinders 3, 6 and 9 as added. In accordance with my invention, the armature shaft of a two pole, shuttle type ignition machine is connected with the cam shaft of the engine by gearing having a ratio of 2:9, and the periods of maximum voltage corresponding to the missing cylinders 3, 6 and 9 are made inoperative. To do this, in accordance with the first example, I can make use of an interrupter after the manner of Fig. 13 and a distributor disk after the manner of Fig. 24, or of an interrupter-wiper-disk after the manner of Fig. 14, combined with a distributor-disk after the manner of Fig. 15.

Fig. 16 is the scheme of a six-cylinder engine, wherein the cylinders are arranged in two planes and displaced 90° in each plane, the two series actuating two cranks arranged in 180° relation with each other. The engine requires an irregular order of ignition in accordance with Fig. 17. In accordance with the invention, the engine is to be imagined as completed, in the manner referred to, to make up the scheme of the eight cylinder engine of Fig. 18. There is obtained thereby the regular order of ignition of Fig. 19 with two excess ignitions, which correspond to the missing cylinders 3 and 7. For the suppression of the excess ignitions, there may be used either an interrupter-cam-disk according to Fig. 20 in combination with a distributor-disk according to Fig. 25, or an interrupter-cam-disk according to Fig. 21 in combination with a distributor-disk according to Fig. 22.

The invention is not necessarily confined

to four-cycle engines, but can by appropriate adaptation be employed with like effect for two-cycle and six-cycle engines, and, in general for all engines operating with any desired cycle. It is likewise immaterial to the essence of the invention whether a two-pole or a multipole ignition machine is employed.

In the appended claims, "regular intervals" is used in the sense of intervals which recur periodically after equal lapses of time whenever the engine is rotating at constant speed, while "irregular intervals" is used in the sense of intervals which recur after unequal lapses of time whenever the engine is rotating at constant speed.

What I claim is:—

1. The combination with a multiple cylinder combustion engine requiring ignition at irregular intervals, of an ignition machine adapted to produce ignition voltages at regular intervals, means for operating the ignition machine at such speed relative to the speed of the engine that the regular interval between ignition periods of the ignition machine is a common divisor of the irregular intervals of ignition of the engine, and means for selecting and distributing to the individual cylinders of the engine those generated voltages which coincide in time with the irregular ignition periods of said cylinders.

2. The combination with a multiple cylinder combustion engine requiring ignition at irregular intervals, of an ignition machine adapted to produce ignition voltages at regular intervals, means for operating the ignition machine at such speed relative to the speed of the engine that the regular interval between ignition periods of the ignition machine is the greatest common divisor of the irregular intervals of ignition of the engine, and means for selecting and distributing to the individual cylinders of the engine those generated voltages which coincide in time with the irregular ignition periods of said cylinders.

3. In combination with a multiple cylinder combustion engine requiring ignition at irregular intervals, of an ignition machine adapted to produce ignition currents at regular intervals, means for operating the ignition machine at such speed relatively to the speed of the engine that the regular interval between ignition periods of the ignition machine is a common divisor of all the irregular intervals of ignition of the engine, and means for rendering inoperative the excess available ignition currents of the ignition machine.

4. The combination with a multiple cylinder combustion engine requiring ignition at irregular intervals, of an ignition machine adapted to produce ignition currents at regular intervals, means for operating

the ignition machine at such speed relative to the speed of the engine that the regular interval between ignition periods of the ignition machine is the greatest common divisor of all the irregular intervals of ignition of the engine, and means for rendering inoperative the excess available ignition current of the ignition machine.

5. The combination with a multiple cylinder combustion engine requiring ignition at irregular intervals, of an ignition machine adapted to produce ignition currents at regular intervals, means for operating the ignition machine at such speed relatively 10 to the speed of the engine that the regular interval between ignition periods of the ignition machine is a common divisor of all the irregular intervals of ignition of the engine, and a distributor with contact pieces 15 for conducting the excess ignition currents to those cylinders of the engine which contain no explosive gas at the time.

Copies of this patent may be obtained for five cents each, by addressing the "Commissioner of Patents, Washington, D. C."

6. The combination with a multiple cylinder combustion engine requiring ignition at irregular intervals, of an ignition machine 25 adapted to produce ignition currents at regular intervals, gearing operatively connecting the engine and ignition machine of such ratio that the regular interval between ignition periods of the ignition machine is a common divisor of all the irregular intervals of ignition of the engine, and a distributor and connections for conducting the excess ignition currents to those cylinders which contain no explosive gas at the 30 time.

In testimony whereof I affix my signature, in presence of two witnesses.

GOTTLOB HONOLD.
